DESIGN FOR A JAR FOR COSMETICS

Jean E. Vivaudou and Henry G. Lubin,
New York, N. Y.

Application May 11, 1942, Serial No. 106,860

Term of patent 7 years

To all whom it may concern:

Be it known that we, Jean E. Vivaudou and Henry G. Lubin, subject of Great Britain and citizen of the United States, respectively, both residing at New York city, in the county of New York and State of New York, have invented a new, original, and ornamental Design for a Jar for Cosmetics, of which the following is a specification, reference being had to the accompanying drawing, forming a part thereof.

In the drawing:

Fig. 1 is a perspective view of a jar for cosmetics, showing our new design;

Fig. 2 is a top plan view of the same;

Fig. 3 is a front elevational view of the same;

Fig. 4 is a side elevational view of the same.

We claim:

The ornamental design for a jar for cosmetics, as shown.

JEAN E. VIVAUDOU.
HENRY G. LUBIN.
